STORM SIMULATING DEVICE

Filed Oct. 21, 1927

UNITED STATES PATENT OFFICE

FRANK SCHALKENBACH, OF NEW YORK, N. Y.

STORM-SIMULATING DEVICE

Application filed October 21, 1927. Serial No. 227,695.

The present invention relates to devices which produce sounds of different characters in imitation of other natural or artificial sounds and deals particularly with storm simulating devices. The construction embodying the present invention, and by means of which the noises of a storm are imitated, has been carefully designed to provide a means for producing every component sound which 10 contributes to the final effect of the storm.

Having ascertained the individual sounds which predominate to give the natural effect, an object of this invention is to provide an apparatus capable of reproducing or imitating such individual sounds and producing an ultimate sound of which such individual sounds are component parts, the ultimate sound being an imitation of a characteristic natural storm.

20 A further object of the invention is to provide a device of the above character which is controlled by a single operator, the individual sounds being produced by mechanism carried upon a supporting structure and 25 actuated at the proper times by the operator.

With the problem in mind of producing a resultant sound having the exact characteristics of a natural storm, the following apparatus has been designed, and a detailed description thereof will now be given in connection with the accompanying drawings, wherein:

Fig. 1 is a view in elevation, partly broken away, showing the storm simulating device 35 of the present invention.

Fig. 2 is an end view, partly broken away, showing the device of Figure 1.

Fig. 3 is a section showing the manner in which shot are discharged from the box at the 40 top of the device into the upper channel.

Fig. 4 is a view in section showing the manner in which shot are discharged from one channel into another.

Fig. 5 is a sectional view taken on line 45 5-5 of Fig. 1 and looking in the direction of the arrows.

Fig. 6 is a sectional view taken on line 6-6 of Fig. 1 and looking in the direction of the arrows.

50 Fig. 7 is a view in section, partly broken

away, showing the valve mechanism controlling the discharge of air from the wind box.

In the above drawings, *a* indicates a supporting frame which may be of any suitable construction adapted to carry the elements described hereinafter as producing sounds in imitation of certain sounds which are produced in natural storms. At one side of the frame downwardly drooping supporting arms *b* are secured, these arms serving to 55 carry a steel sheet *b'* for producing the sounds to imitate thunder. This sheet is secured to the arms *b* by means of links *b*² which enable the sheet to vibrate with as little damping from the arms *b* as possible. To produce the 60 desired noises the sheet is either struck by a muffled lever or drum stick, or shaken by hand.

The top of the frame *a* carries a box or receptacle *c* to receive a supply of shot. An aperture *c'* is provided at one end of the box for the discharge of the shot and a shutter *c*², pivoted to the box at *c*³, controls the discharge of the shot from the box. Handle *c*⁴ is provided to control the action of the shutter *c*² and spring *c*⁵ serves to hold the shutter in either opened or closed position. When the shutter is closed, the spring exerts a closing force on one side of the pivot *c*³ and when open the spring exerts a force on the other side of the pivot to maintain the shutter in such open position. A spring finger *c*⁶, secured to one side of the box, is provided with a handle *c*⁷ extending through the other side thereof. This handle may be moved back and forth to 70 rake the shot at the opening in the box and clear such opening of any obstructions which might exist.

An aperture *a'* is formed in the upper portion of the supporting frame *a* and permits 75 the shot, which falls from the box *c*, to drop upon an upper channel *d*. Channel *d* is provided with a drum skin *d'* and the shot falling upon this drum skin and rolling down its length produces a muffled sound in imitation 80 of the sound of rain falling upon certain objects. The channel *d* is pivoted at *D*² to the upper portion of frame *a* and, at its other end *d*³, is pivoted to the intermediate channel *e* having a wooden bottom *e'*. The shot, in 85 90 95 100

falling from the channel d into e may impinge against a suitable baffle d^4 covered with drum skin similarly to the channel d and its continued movement down channel 5 e produces sounds which imitate the sound of rain falling on wooden objects and the like. The channel e , at its lower end, is pivoted to the lower channel f , as indicated at e^2 , the channel f being formed with a thin metal 10 bottom f' . The effect of the shot passing along this channel produces a sound which is similar to that of rain falling upon a tin roof. A baffle e^3 similar to baffle d^4 may be provided to guide the shot in falling from channel e 15 into channel f , and the shot are discharged from channel f into a box a^2 secured to the supporting frame a by a bracket a^3 . If desired a baffle a^4 may be provided against which the shot impinge as they fall from 20 channel f into the box.

Positioning rods a^5 are secured to the top of the supporting frame and provided with slots a^6 which receive studs d^5 , e^4 and f^2 secured to the respective channels d , e , and f . 25 Wing nuts are threaded on these projecting studs and serve to secure the channels in desired positions so that the inclination thereof may be varied to change the rate at which the shot is cascaded from top to bottom and 30 the character of the sound produced. The greater the inclination of a channel, the more violent will be the sound produced by the shot passing down its length.

As the operator sits at the frame, he places 35 his feet upon bellows g and by pumping them, forces air through pipes g^7 into wind box g^2 . This box is carried upon the upper portion of the frame a and is provided with fixtures to imitate the howling of the wind and 40 other storm sounds. By varying the pumping of the bellows the intensity of the sounds may be increased or diminished as desired.

In the present construction, a whistle g^3 is provided which imitates the crying of a 45 baby and the operation thereof is controlled by a valve g^4 . To imitate the howling of the wind, a nozzle g^5 , formed on the wind box g^2 , directs wind against a hollow copper ball g^6 . The blast of wind against this ball is 50 controlled by a valve g^7 , the valves g^4 and g^7 being shown in greater detail in Figure 7. A vertical standard g^8 is secured to the wind box g^2 and carries the ball g through a swivel connection g^9 . By means of this connection, 55 the ball may be turned on a horizontal or vertical axis to vary its position with respect to nozzle g^5 and in this manner the blast of wind against aperture g^{10} in the ball is caused to produce notes of varying pitch or 60 character.

The valves for controlling the flow of air to the crying or wind imitating devices are shown in Fig. 7, wherein plug valve, one of 65 which is shown at h , are seated at h' against the pipes leading to the instruments, the

valves being maintained in this position by means of leaf springs h^2 . A pin h^3 , carried upon lever h^4 engages the spring h^2 to unseat the valve upon proper movement of the lever. This lever is pivotally mounted at h^5 upon 70 the wind box g^2 and its depending arm h^6 is engaged by a cam h^7 to move it outwardly. This movement opens the valve and permits air to flow to the desired instrument. The cam h^7 is mounted upon shaft h^8 which is carried by the wind box and is provided with an operating lever h^9 . 75

I will be seen that the operator, sitting in front of the apparatus and working the bellows g , may imitate the various sounds of the wind, thunder, and rain which are found in natural storms. The entire mechanism is designed to permit this operation to be effected by a single person and the elements are constructed to permit a desired variation in 80 the character of the sounds produced to produce imitations of storms of varying character. 85

I claim as my invention:

1. A storm simulating device comprising 90 a supporting frame, a plurality of channels carried by the frame, means to position the channels to enable objects to cascade from one to another in traversing the lengths thereof, a container carried above the channels, means to control the discharge of objects therefrom, and means forming the bottom of the channels to cause each to produce a distinctive sound as the objects roll along their lengths. 100

2. A storm simulating device comprising 105 a supporting frame, a plurality of channels carried by the frame, variable means to position the channels to enable objects to cascade from one to another in traversing the lengths thereof, a container carried above the channels, means to control the discharge of objects therefrom, and means forming the bottom of the channels to cause each to produce a distinctive sound as the objects roll 110 along their lengths. 115

3. A storm simulating device comprising 120 a supporting frame, a plurality of channels carried by the frame, means to position the channels to enable objects to cascade from one to another in traversing the lengths thereof, one of the channels including a drum skin over which the objects roll, another channel, including a wooden surface, a third channel, including a metal surface, a container carried above the channels, and means to control the discharge of objects therefrom. 125

4. A storm simulating device comprising 130 a supporting frame, a plurality of channels carried by the frame, means to position the channels to enable objects to cascade from one to another in traversing the lengths thereof, one of the channels including a drum skin over which the objects roll, another channel,

including a wooden surface, a third channel, including a metal surface, baffles for controlling the movements of the objects from one channel to another, a container carried above the channels, and means to control the discharge of objects therefrom.

5 This specification signed this 17" day of October, A. D. 1927.

10 FRANK SCHALKENBACH.
